PROJECTION PHOTOGRAMMETRIC
PLOTTING APPARATUS

Ermenegildo Santoni, Florence, Italy

Application August 3, 1949, Serial No. 108,396
In Italy August 28, 1948

3 Claims. (Cl. 88—24)

1

The device relates to an apparatus which has the purpose of effecting the plotting of pairs of photographs, either aerial, nadiral and oblique, and terrestrial; the whole with a new arrangement and combination of members which make the construction particularly simple in relation to all which are already known.

The apparatus is shown as an embodiment by the accompanying drawing, in which:

Fig. 1 shows a schematic embodiment of the unit;

Fig. 2 shows a side view with partial sections, in different planes, of a form of realization;

Fig. 3 is a partial top view;

Fig. 4 is a partial front view;

Figs. 5 and 6 show details; and

Fig. 7 is a variation of Fig. 5.

As it is to be seen in the schematic Fig. 1, the apparatus is composed of two symmetrical groups, of which the left one, in relation to who is looking at the drawing, is only partially represented and thus it is to be intended complete of the members represented in the right group; a detailed description of this right group will be given. As it is seen in Fig. 1, a base 1, by means of a column 2, holds a horizontal guide 3, along which the slide *bx* can run. This slide bears an orthogonal guide 4, along which the slide *by* can run, and the latter, at its turn, bears a vertical guide 5 along which the slide *bz* can run.

The slide *bz*, by means of a bored abutment, holds a tubular axle 6. The axle 6 by means of a side arm 6' bears the axle 6''. This axle serves as a support for the arm 7 which holds the tube 8 and, bent in its upper part, the plate dark slide 9.

A turntable axle, which bears the universal joint 10, holding the guide rail 11, is housed in the inside of the tubular axle 6. The guide rail is extended at its upper section into a tubular form in order to house a small slideable rod 11', which ends in a spherical joint 12, which connects the rod to the plate dark slide 9. The arm 7 holds the plate dark slide 9 by means of a system of cross guides, schematically indicated in the drawing by *x*—*y*, so that the plate dark slide be susceptible to move in its own plane without changing the orientation.

The same plate dark slide is induced to move in the plane *x*—*y* by the polar movement of the rod 11 around the universal joint 10.

By such movements, the centre of the spherical joint 12 describes a plane which is to be intended as a plane in which, theoretically, the photographic image, of which the plotting is effected,

ought to lie. In effect, the photographic image *fd* is displaced laterally, according to *x* and to *y* in order to be able to observe it from the bottom up towards the top by means of an optical system, 5 the tubular end 8 of which is held by the same arm 7. An objective *O*1 is placed in the upper section of the tube 8 and a ground glass with the collimating mark *m* is placed in the lower part. The image of the point *pd* of the photograph, by means of the objective *O*1, is formed in correspondence of the mark *m*.

The position of the members is such that if the plate dark slide 9 is horizontal, the axis of the tube 8 results to be vertical, and if in said condition 15 the guide rail 11 is brought to a vertical position, the image of the central (main) point of the photograph is formed on the mark *m*. The conditions of a correct mechanical projection of the photograph thus result to be realized.

20 The above described arrangement of the members allows to introduce the component *bx*, *by*, *bz* of the base, which can be introduced by half in each of the two groups of the instrument.

Furthermore, by means of the rotations around 25 the axle 6 (generally called ω) and around the axle 6'' (generally called φ) the inclination corresponding to the condition of exposure can be given to the photograph. The value of the swing *k* is obtained by rotation of the same photograph in its own plane by means of a rotational ring 9'.

30 The three movements ω — φ —*k* are provided of worm screw control members and of angular graduations, not represented, for simplicity of drawing, in Fig. 1.

35 The image of the photograph formed in correspondence of the mark *m* is brought into the range of the ocular lens *Od* by means of the mirror *S*1, the objective *O*2, the Amici prism *A*, the objective *O*3 and the mirror *S*2. The optical distances, respectively between the objective *O*2 40 and the mark *m* and the objective *O*3 and the focal plane of the ocular lens *Od* are established, while the distance *O*2, *O*3 is variable in consequence of the linear displacements (*bx*, *by*, *bz*) and of the angles ω — φ of the plate dark slide.

45 The distance *O*2, *Od* is freely variable for, in this section, the optical beams are parallel. The two guide rails 11 and 13 are reunited by a spherical joint 14 to a frame 15, which, as a rule in 50 all the apparatus of this kind, is movable in accordance to the three directions *Z*—*K*—*Y* by means of suitable guides realized with already known arrangements. Their schematic representation thus consequently is limited only in 55 Fig. 1.

Figs. 2, 3, 4 represent, for the left unit, a form of realization of the invention, to which it seems possible to give the preference, but which is not to be considered the sole. The support 2 with the guide 3, the slide *bz* and the slide *by*, represented in Fig. 1, are excluded from Figs. 2, 3, 4.

In Fig. 3 the photogram *fs* is considered like a transparent sheet, in order to render the lower members visible.

The vertical guide 16 of Fig. 3 corresponds to the vertical guide 5 of Fig. 1. Along the guide 16 the support 17 (*bz* of Fig. 1) can slide. This support holds the tubular axle 18, which bears, at one end, the fork 18' and at the opposite end the sector 19, on which the worm screw 20, for the introduction of the rotations ω , acts. The fork 18' holds the frame 21 which by means of the geared sector 21''' and the worm screw 22 can rotate around the axis φ . The worm screw 22 is held by an arm 18'', secured to the tube 18.

The frame 21 bears two guides 21' and 21'' along which a frame 23 can slide; said frame 23 bears, at its turn, two guides 23', 23'' along which the plate 24 can slide; said plate constituting the plate dark slide. The plate 24 can thus slide in the plane according to the described cross movement. Said plate bears an appendix 24', to which the spherical joint 25, holding the spherical end of the pin 26, slidable in the tube 27 is applied.

The tube 27 is, at its turn, held by the universal joint 28 which results to be concentrical to the intersection of the two axes ω , φ of rotation of the plate dark slide. Said tube 27 extends downwards into a section 27' constituted by a hollow cylinder sector, which adheres to the sphere or ball 28' by the action either of a lever 29 or of a spring 30, as it is clearly seen in Fig. 5 the small lever 29 is hinged to a support 29' secured to the pin 15' which holds the sphere 28', and the spring reacts between said small lever 29 and said support 29'. The guide rail 11, corresponding to the right unit, comes to lie against the same sphere 28', on the opposite side.

The photogram *fs* is mounted on the turnable ring 24'' in order to give the swing *k*, as in Fig. 1.

All that is referred to the plane movement of the plate, to the polar movement of the guide rod 27' and to the rotation ω , φ , *k*, is realized by the aforescribed members; the whole being pre- edently described and illustrated in the schematic Fig. 1.

The same frame 21 holds the tube 31, which bears upperly the objective *O*1 and lowerly the mark *m*. This tube 31 is turnable around its own axis and bears, by means of a fork, the tube 32 in which the objective *O*2 is secured. On the same hinging axis of the tubes 31 and 32, is placed the turnable mirror *S*1, which can automatically receive the half of the relative rotations of the two tubes by means of a differential gear system or an articulated parallelogram of the already known types, and which thus, is retained unnecessary to describe.

A similar arrangement is provided for the tube 33 which bears the objective *O*3 for the mirror *S*2 and for the tube 34 which bears the ocular lens *Od*.

The tube 34 is held by the tube 35 by means of a transversal element 36 which also holds, in a similar way, the right ocular lens *Od*. The sliding of the two oculars along the transversal element 36 allows to effect the interpupillary variation. The transversal element 36 is, at its

turn, held by an arm 37 borne by the same base 1 (Fig. 1).

The external tube 38 which holds the Amici prism A serves as a connection of the two tubes 32, 33 in order to complete the optical travel.

The rotation of the Amici prism can be effected by hand, for the convenient rectification of the orientation relative to the two images in the oculars *Od*, *Os* (Fig. 1).

Fig. 6 represents a means to effect the adjustment of the apparatus to the focal distance of the shooting camera of the photograms to be utilized. For this purpose the plate 26' bears a threaded hole in which a threaded appendix 25', which is lowerly integral to the member 25'', forming the hollow spherical housing of the spherical joint 25 can be, more or less, screwed into.

In Fig. 7 a variation of Fig. 5 is shown, and it is adapted for the introduction of photogrammetric bases of a small entity; in this example, instead of the only sphere 28' (see Fig. 5), two spheres 28a and 28b are provided and they are conveniently located, each other, at a certain distance and a guide rail respectively 11, 27' is brought to lie against each of them. The two spheres 28a, 28b are supported by a pin 15'' similar to the pin 15', of Fig. 5.

It is intended that the drawing only constitutes a schematic form of example, given only as a practical demonstration of the device; said device being susceptible of variations in its forms and arrangements without departing from the ambit of the concept which informs the same device.

Having now particularly described and ascertained the nature of my said invention and in what manner the same is to be performed, I declare that what I claim is:

1. A mechanical projection photogrammetric plotting apparatus, composed of two symmetrical sections, each of which comprises a guide rod, universally hinged in the projection centre; a support rotatable around the same centre according to two orthogonal axes, a cross-slide on said support for holding a frame on which the photogram is mounted; a connection by means of a spherical joint between the upper end of the guide rod and said frame, so that for all the angular movements of the guide rod, there are such corresponding displacements on the cross-slide of the photogram to be in a condition to bring any point of it in correspondence to an optical system carrier by said support, said apparatus being characterized by the fact that the spherical joint of connection between said guide rod and said photogram-bearing frame is applied to a lateral appendix of said frame so that the centre of the photogram is displaced laterally and outwardly (in accordance to the major component of the stereoscopic base) and on the side of the operator (in accordance to the minor component), the end of said optical system of collimation being brought onto said support of the cross-slide, said optical system being arranged under the same photogram and being made up of a first tube which at the top bears an objective lens and at the bottom a glass with a mark, said first tube holding under the mark, a first box which contains a first pivotable mirror which rotates for an half of the angle over which said first tube and a second tube connected to said first box rotate relative to each other, said second tube bearing a second objective and holding a third coaxial tube, rotatable and slidable on it, and

containing an Amici prism, said third tube being in turn connected to a fourth tube, bearing a third objective and united to a second box, similar to the first, containing a second pivotable mirror, said box being in turn connected to a fifth tube, to which the observation ocular is applied.

2. A mechanical projection photogrammetric plotting apparatus, as described in claim 1, characterized furthermore by the fact that it also comprises: two guide rods, formed in the lower part by hollow cylinder sectors, single sphere (the centre of which represents the plotted point) borne by a support movable in accordance with three spacial directions X, Y, Z; spring means arranged so as to keep said lower hollow cylinder sector-shaped parts of said guide rods in contact against said sphere.

3. A mechanical projection photogrammetric plotting apparatus, as described in claim 1, characterized furthermore by the fact that it also

comprises: said guide rods formed in the lower section by hollow cylinder sectors, two spheres spaced apart from each other; spring means arranged so as to keep said lower hollow cylinder sector-shaped parts of said guide rods in contact against each of said spheres.
